(57) **CLAIM**

The ornamental design for a triangular nail varnish receptacle, as shown and described.

DESCRIPTION

FIG. 1 is a perspective view of a triangular nail varnish receptacle;

FIG. 2 is a front elevation view of the triangular nail varnish receptacle of FIG. 1;

FIG. 3 is a back elevation view of the triangular nail varnish receptacle of FIG. 1;

FIG. 4 is a right-side elevation view of the triangular nail varnish receptacle of FIG. 1, the left-side elevation view being a mirror image of the right-side elevation view;

FIG. 5 is a top plan view of the triangular nail varnish receptacle of FIG. 1; and,

FIG. 6 is a bottom plan view of the triangular nail varnish receptacle of FIG. 1.

The broken lines form no part of the claimed design. The claimed design extends to the broken line boundary in FIG. 6, but does not include the boundary or the area within the boundary.
